(57) **CLAIM**

The ornamental design for a combined cord protection cover plate with concealed flat plug, as shown and described.

DESCRIPTION

FIG. 1 is a front and top perspective view of a combined cord protection cover plate with concealed flat plug design showing my new design.

FIG. 2 is a rear and bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an enlarged view of a portion indicated with "9" in FIG. 1.

In the drawings, the even dash-dot broken lines are for the purpose of illustrating portions of the combined cord protection cover plate with concealed flat plug that form no part of the claimed design. In FIGS. 1 and 9 the longer dash-dot broken lines are for the purpose of illustrating boundaries of the enlarged portions of the claim that form no part of the claimed design.
